EXTENSIBLE DRYING RACK

Woodward H. Gillespie, Louisville, Ky.

Application June 26, 1947, Serial No. 757,234

7 Claims. (Cl. 211—96)

1

This invention relates to brackets of the disappearing type, and relates in particular to a multiple type of bracket which may be collapsed into a small, compact sheath.

It is an object of this invention to provide a collapsible bracket of the type having a rod like sheath that is readily inserted in a cabinet, stove, or the like, and which may be extended to provide a plurality of hanging racks.

A further object is the provision of a collapsible bracket providing a plurality of hanging racks pivotally mounted so as to lock in spread position.

Another object is the provision of a collapsible rack providing a plurality of hanging racks, which may be frictionally clamped together for conjoint movement into retracted position.

A further object is the provision of a collapsible rack of simple construction which is inexpensive to manufacture and which may be collapsed into a small volume or spread to provide a plurality of racks.

In accordance with the present invention I provide a sheath which is receivable in a cabinet, stove or the like, and which contains the racks in collapsed position. A shoe or bearing member in the sheath carries a plurality of racks in the form of rods pivoted thereon, and the end of the sheath has slots which receive the rods in spread position to hold them for use.

The invention will be described in greater detail in connection with the accompanying drawing which shows a preferred embodiment of the invention by way of example, and wherein:

Figure 1 is a top view in section with parts broken away, and showing the invention in operative position.

Figure 2 is a plan view showing the invention in inoperative position.

Figure 3 is a section taken on line 3—3 of Figure 1.

Figure 4 is a section taken on line 4—4 of Figure 1, and

Figure 5 is a plan view partly in section of a detail.

Referring to the drawing, Figure 1, there is shown a tubular sheath 1 of metal or other suitable material, to which may be secured a flange 2 in any suitable manner, as by brazing. The device may be installed in a cabinet or stove wall, shown diagrammatically at 3, and is fastened in position by screws or the like extending through holes 4 in the flange into the wall. Sheath 1 may be split longitudinally for a portion of its length by removal of diametrically op-

2

posite portions to provide runways 5 and 6 terminating at 7 adjacent the flange to provide a stop. The separated ends of the sheath may be united by a plate 8 having tabs 9 extending through suitable diametrically opposite holes in the sheath wall, the tabs being peened or riveted to hold the sheath portions in proper position.

A shoe 14 located within the sheath for sliding movement therein, serves as a bearing member, and preferably has diametrically opposite guide projections 15 which project into the runways 5 and 6 and serve to prevent turning of the shoe in the sheath. In forward position of the shoe, the projections 15 engage the stop 7 to limit movement thereof. However, any other suitable means may be provided for this purpose. A rod 16, of suitable diameter extends through the shoe and at its opposite end preferably carries a cap 17 adapted to fit over the end 18 of the sheath. Cap 17 may be held on rod 16 by a threaded connection, or in any other suitable manner, or it may be carried by one of the other rods herein-after referred to, if desired. The shoe 14 has bifurcated ends or prongs 21, 22 extending therefrom and a pin 23 extends through said prongs and through the ends 24, 25 of rods 26, 27, whereby said rods are supported for pivotal movement on said pin. The ends 24, 25 are offset in relation to the respective rods so that with the ends 20 crossed the rods 16, 26 and 27 lie substantially in a common plane, as shown in Figure 4.

Rod 16 preferably carries at its outer end a friction clamp comprising in the preferred embodiment a pair of spring plates 30, 31 which may be secured thereto by pins 33, or in any other suitable manner, and when rods 16, 26 and 27 are in parallel or collapsed position, as shown in Figures 3 and 5, the outer ends of rods 26, 27 are resiliently held between plates 30, 31. In this position, the shoe 14 and the rods 16, 26 and 27 may be telescoped into the sheath 1, the shoe 14 being slid inwardly until cap 17 engages the end of sheath 1. Cap 17 has recesses or dimples 34 in the interior surface which engage the nodules 35 struck up from the surface of sheath 1, so that the cap is firmly held on the end of the sheath, but can be withdrawn when desired.

The end 18 of sheath 1 is slotted as indicated at 36, 37, the slots lying substantially in the same plane as rods 26 and 27. When the rods 26, 27 are in spread position, as shown in Figures 1 and 4, rod 26 frictionally engages an edge of slot 36 and rod 27 frictionally engages an edge of slot 37, so that rods 26, 27 are frictionally held in spread position. In this position, the rods 16, 26 and 27

are available for supporting towels or other wet articles which are to be dried.

When it is desired to place the rack in inoperative position, the towels, etc. are removed from the rods, and the rods 26, 27 are pivoted inwardly to disengage them from the slots 36, 37 and are swivelled to parallel position with the rod 16, the ends of the rods 26, 27 being received and gripped by the spring plates 30, 31. The combined widths of the rods are less than the internal diameter of the sheath, so that in this position, the whole assembly of the shoe and rods may be telescoped into the sheath, and the sheath is closed by the cap 17 engaging the end thereof. To place the rack in operative position, it is necessary only to remove the cap and withdraw the rods and shoe thereby until the projections 15 engage the ends 7 of the runways, and then the rods 26, 27 may be spread to frictionally engage in the slots 36, 37. The spacing of the ends 7 of the runways is so related to the bottoms of slots 36, 37 that the rods may be spread the desired amount, and if desired, this distance may be such as to lock the rods in spread position.

From the foregoing description, it will be apparent that I have provided an extensible rack which may be readily attached to the wall of a cabinet, stove, or the like, and may be readily collapsed so as to be out of the way when its use is not desired. The rack is sturdy and provides a multiplicity of rods upon which articles may be hung. While I have shown three such rods, it will be apparent that any desired number of such rods may be employed. Various other modifications may be made in the invention without departing from the spirit or scope thereof.

What I claim as my invention and desire to secure by United States Letters Patent is:

1. A collapsible rack comprising a tubular sheath, the ends of said sheath providing slots, a bearing member slideable in said sheath, and a plurality of rods, at least two of which are pivoted to said bearing member for movement in opposite directions and which are adapted to be received in said slots, the slots being oppositely, slightly offset relative to the rods, whereby each rod is held in frictional engagement with a side thereof to hold said rod in spread position.

2. A collapsible rack comprising a tubular sheath, the end of said sheath having slots, a shoe slideable in said sheath and having guide projection means preventing rotation therein, and a plurality of rods, at least one of which is pivoted to said shoe and is adapted to engage in one of said slots, the slot receiving said rod being slightly offset relative thereto, whereby the rod is held in frictional engagement with a side thereof to hold said rod in spread position.

3. A collapsible rack comprising a tubular sheath, the ends of said sheath providing slots, a bearing member slideable in said sheath and carrying a plurality of rods pivoted therein, the pivoted ends of said rods being offset in relation

to said respective rods to allow said rods to lie substantially in a common plane and cross at the pivot.

4. A collapsible rack comprising a tubular sheath, divided for a portion of its length by longitudinal slots, a shoe slidably mounted in said sheath and having projections entering said slots, said sheath having at least one slot in its one end, a plurality of rods carried by said shoe, at least one of which is pivoted on said shoe and adapted to engage in an end slot in spread position, and a cap carried by one of said rods.

5. A collapsible rack comprising a tubular sheath having slots in the end thereof, a shoe slidably mounted in said sheath, stop means adjacent the slotted end to limit withdrawal of said shoe, a plurality of rods carried by said shoe, two of which are pivoted on said shoe, each being adapted to engage one of said slots when the rods are in spread position, and a friction clamp carried by one of said rods for clamping said rods together in collapsed position.

6. A collapsible rack comprising a tubular sheath having diametrically opposite slots in one end thereof, and having longitudinal dividing slots; a shoe slideable in said sheath and having projections entering said dividing slots, a rod secured in said shoe at one end and carrying a cap at its opposite end; a pair of rods pivoted at their inner ends in alignment with said first rod, the inner ends of said pivoted rods being offset in relation to the rod, whereby said rods lie in a common plane, and friction clamp means for securing said rods together, said pivoted rods being receivable in said end slots in spread position.

7. A collapsible rack comprising a tubular sheath having a flange at one end thereof and having slots in said end, and longitudinal dividing slots in the opposite end of said sheath, a shoe slideable in said sheath having projections entering said dividing slots, rods carried by said shoe, certain of said rods being pivotally mounted and movable laterally to be received in said end slots, and a cap carried by one of said rods and adapted to close said sheath end in collapsed position of said rack.
